Primary Examiner — Llorellys Martinez-Rivera(74) *Attorney, Agent, or Firm* — The Webb Law Firm(57) **CLAIM**

The ornamental design for a mounting rail, as shown and described.

DESCRIPTION

FIG. 1 is a top perspective view of a mounting rail showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The mounting rail is shown with a symbolic break in its length. The appearance of any portion of the mounting rail between the break lines forms no part of the claimed design.
